CORRUGATED SHEET METAL BUILDING
CONSTRUCTIONJoseph M. Brinker, Washington, D. C., assignor
to Elizabeth M. Brinker, Washington, D. C.

Application July 6, 1942, Serial No. 449,930

3 Claims. (Cl. 108—1)

This invention relates to steel building construction in which corrugated sheets of relatively light gauge steel form the basic material of which the various structural units are fabricated.

One of the objects of the invention is to provide hollow vertically corrugated sheet metal columns for the load bearing units, with a novel assemblage of such columns, in plurality, to form the corners of the building.

Another object of the invention is the employment of such load bearing units in spaced relation bridged by horizontally corrugated sheets secured thereto.

A further object of the invention is the provision of a wall construction from three sided columnar units, vertically corrugated and laterally telescoped one within the other so that together they form an expandable wall adapted to be spread or contracted to fit between fixed vertical units, as between window frames or a window frame and door frame.

Still another object of the invention is a wall structure as described, preliminarily expandable, and then fixed in lateral dimensions and reinforced by the application and securing thereto of horizontally corrugated metal sheets.

Another object of the invention is the construction of joists, rafters and purlins in the form of twin ridged members of longitudinally corrugated sheet metal in which load bearing strength is derived from the depth of the ridges.

A further object of the invention is to provide attic joists, each of twin ridged corrugated cross-section as described, in which the lower end portion is bent upwardly at the angle of the roof pitch and reversely ridged, forming with the horizontal portion of the joist a pocket receiving the lower end of the roof rafter, the latter telescopically fitting the upturned end of the joist.

Another object of the invention is a roof peak construction in which meeting twin ridged rafters have integral angular lapping ridge tops and flange portions, and lapping ridge side portions, suitably secured.

Still another object of the invention is a ceiling construction in which the ceiling area is bridged by twin ridged joists having lateral flanges and spaced apart, with sheet metal plates filling the spaces between adjacent joists, resting on said flanges, and plates secured to the under sides of said joists and coextensive therewith in width.

A further object of the invention is a floor construction comprising the twin ridged joists laid

in contiguous adjacency and covered with concrete of such thickness as to extend above the ridges of said joists to the desired depth.

Another object of the invention is a foundation corner construction in which the floor joist is secured to the concrete foundation by a lag screw anchored to a plug in the concrete, and in which the wall channel is secured to the floor by a screw passing through said channel, a plug or aperture in the concrete floor above a ridge of the joist and into the metal of said ridge whereby a metal to metal securing of the wall channel is obtained.

Another object of the invention is an alternative foundation construction in which the steel wall construction of the building is surrounded in spaced relation by a wall of corrugated sheet metal in the excavation, the space between the building wall and said surrounding wall being filled with a suitable moisture-proof material.

Other objects of the invention will appear as the following description of a preferred and practical embodiment thereof proceeds.

In the drawings which accompany and form a part of the following specification and throughout the several figures of which the same characters of reference have been employed to designate identical parts:

Figure 1 is a perspective view of a building in course of construction, illustrating certain of the features of the subject invention;

Figure 2 is a cross-section illustrating features of construction of the wall, roof, floor and foundation;

Figure 3 is a perspective view of one form of wall construction;

Figure 4 is a perspective view of a modified form of wall construction;

Figure 5 is a perspective view showing thelapping upper ends of abutting roof rafters;

Figure 6 is a perspective view showing the roof rafter pocket formed at the end of an attic joist;

Figure 7 is a vertical section showing a detail of ceiling construction;

Figure 8 is a vertical section showing a detail of the foundation corner;

Figure 9 is a horizontal section through a corner of the building;

Figure 10 is a horizontal section through an alternative form of foundation construction.

Referring now in detail to the several figures, numeral 1 represents the corner construction as a whole, comprising three vertical columns 2, 3 and 4 of rectangular cross-section and each consisting of a corrugated metal sheet with the cor-

rugations extending in a vertical or load bearing direction. These columns are arranged as shown, with the column 2 at the outside corner and the columns 3 and 4 lying respectively in the front and side wall. At their bottom ends the columns rest in sheet metal channel members 5 and 6, said channel members lying at right angles on the floor 7, and being in abutting relation, as indicated by the broken line 8 in Figure 9, the columns 2 and 4 being in the channel 6, while the column 3 is in the end of the channel 5. An inner right angular strip of corrugated sheet metal 10 extends vertically throughout the height of the room, being secured to the adjacent sides of the columns 3 and 4 by suitable means such as Parker Kalon screws which themselves perforate the metal and thread themselves through the perforations, screwing the contacting parts securely together. Spot welding may also be used as a substitute or an adjunct to the screws.

At suitable intervals between the corners of the building other single vertically corrugated columns, such as the column 11 shown in Figure 9, are placed upright in the base channels and bridged by the horizontally corrugated outer wall sheets 12, these being suitably secured either by screws or spot welding. An outer vertically corrugated right angular strip encloses the outer wall sheets 12 at the corner, being secured thereto and acting to bind the corner columns 2, 3 and 4 together on the outside. Any suitable wall sheet such as the horizontally corrugated metal sheets 13 are secured against the inside of the columns bridging the space therebetween and an inside vertically corrugated corner strip 14 is employed to tie the sheets 13 together. The sheets 13 and including the inside angle strip 14 are covered with any suitable interior finishing plastic.

The outside wall surface may also be covered with any suitable finishing plastic or other material, but is preferably covered by thin stone veneer blocks secured thereto by a suitable plastic cement which keys itself to the horizontal corrugations of the metal sheets 12.

An alternative form of wall construction is shown in Figure 4, in which quadrilateral columns are substituted by the three sided or U-shaped vertical columns 16 which telescope one within the other, as illustrated in Figure 4. This type of wall is particularly desirable between fixed vertical portions of the building, such as spaced window frames or a spaced door and window frame, inasmuch as the columns 16 may be telescoped laterally inwardly or outwardly, thus expanding the wall unit so as to fit any space which it is designed to bridge. It is preferred to have the open side of the final column closed by a reversely arranged telescopic column 17, which in general may be made shallower in lateral depth than the columns 16. For buildings not exceeding one story in height such a wall construction is of adequate rigidity in the absence of any further reinforcement but if the height of the building exceeds one story it is preferred to reinforce the columns by an outer sheet 18 of horizontally corrugated sheet metal secured thereto, or both an inner and outer sheet such as is shown in connection with Figure 3.

Referring now to the roof, floor and ceiling construction, the unit element is a joist, rafter, or purlin having thin ridges with a valley between and lateral flanges at the base of the ridges. In Figure 8, in which two floor joists 19 are shown, the ridges are represented at 20 and 21, the intermediate valley at 22 and the lateral

flanges at 23 and 24. In Figure 6 which shows a ceiling joist, similar parts are designated by the same reference characters and the same is true of the roof rafters, one of which is shown in detail in Figure 5.

Referring now in particular to the floor, it is formed of the floor joists 19 which are arranged in lapping continuity so that the entire floor surface represents a series of parallel ridges and valleys. On this metallic base a slab 25 of concrete is poured to such depth as to provide suitable thickness of concrete over the ridges 19. The concrete which fills the valleys 22 forms depthwise ribs for which the metallic base forms adequate reinforcement.

The attic joists 26 rest at their opposite ends upon channels 27 which overlie the upper ends of the columns 11 or the columns 16, as the case may be. The opposite ends 27 of said attic joists are bent upwardly at an oblique angle corresponding to the pitch angle of the roof and the ridges are reversely pressed, as indicated at 28 and 29 in Figure 6. The upturned ends 27 form with the horizontal portion of the joist 26, a pocket receiving the lower ends of the roof rafters 28, the reverse direction of the ridges 28 and 29 fitting the ridges 20 and 21 of the roof rafters in telescopic relation. Thus, the roof rafters are rigidly retained at their lower ends with the impossibility of their changing their pitch angle under the load of the superimposed roofing material or of snow. The upper abutting ends of the roof rafters 30 on opposite sides of the roof at the peak, are slotted and cut so that the tops 31 and 32 of the overlying rafters are angularly bent upon the ridges of the underlying rafters and the tops 33 of the ridges of the underlying roof rafters are angularly bent to lie within the ridges of the overlying roof rafters and in contact therewith. The end portions 34 and 35, respectively, of the overlying and underlying flanges are similarly bent. The sides of the ridges at the peak are also in lapped relation. The lapping tops of the ridges and flanges are preferably secured by the screws 36, while the lapping sides of the ridges are preferably spot welded together. Thus, a rigid peak structure is produced in a similar efficient and economical manner.

Purlins 37 similar in cross-section to the rafters and joists rest upon the roof rafters longitudinally of the roof, being preferably secured either by screws or spot welding. Said purlins support the roofing sheets 38, the latter being arranged with their corrugations preferably running in a direction from peak to eaves. The purlins 37 are so spaced as to lie beneath the lapping edges 39 of the roofing sheets, the latter being secured to the purlins by screws penetrating into the ridges of the purlins. In Figure 1 the roofing sheets are shown covered with any suitable roofing material 40, such for example as composition shingles. If the attic is to remain unfloored, the attic joists 26 may be arranged in spaced relation, as shown in Figure 7, the spaces between adjacent joists being bridged by the smooth metal sheets 41. The under sides of said joists are also covered with smooth metal sheets 42, the gauge of the latter being somewhat thinner than the thickness of the sheets 41. An uninterrupted metallic ceiling is thus produced which may be covered on the lower side with any suitable finishing plastic or other material.

Reference is now made to the method of anchoring the floor to the foundation and the vertical wall structure to the floor. Figure 2 shows

a concrete foundation composed of the cement blocks 43 which have the conventional core holes 44. The core holes in the top corner blocks are plugged with a substance such as the wooden plug 45 which can be penetrated by a lag screw 46. The end floor joist 19 is placed with its end resting upon the corner block 43 and the lag screw 46 is screwed through the metal of said joist at the bottom of the valley 22 and into the wooden plug 45. A form is then put up at the end of this floor joist and the concrete floor is poured, a wooden plug 47 being imbedded in the concrete above one of the ridges 20 or 21. This plug may be left in or it may be withdrawn, leaving a hole in the concrete extending down to the metal of the floor joist. The base channel 6 is then laid upon the concrete floor overlying the plug 47 or the hole vacated by said plug. A lag screw is then sunk through the metal of the channel 6 through the wooden plug 47 or the hole vacated by said plug and through the top of the underlying ridge of the floor joist. Thus, there is a metal to metal anchorage between the channel 6 and the floor joist and an anchorage between the floor joist and the underlying cement block foundation. It will be understood that the columns of the building walls are suitably secured to the base channel, and thus the entire wall unit is rigidly anchored to the foundation.

In Figure 10 an alternative foundation structure is shown, in which the building wall including the vertically corrugated columns 48 and 49, together with the bridging outer plate 50 extend down to the bottom of the excavation. It is preferred that those portions of the plates 50 which extend below grade be arranged with the corrugations vertical. The excavation represented by the lines 51 and 52 in Figure 10 is sufficiently larger than the building so that the vertically corrugated plates 53 and 54 can be supported within the excavation in spaced relation to the outer walls of the building and extending up to the top of the excavation. The intervening space between the building walls and the plates 51 and 52 is then filled with molten asphalt or any other suitable moisture impervious composition.

The interior partitions of the building, not shown, are similar in construction to the wall structure shown in Figure 3, excepting that the columns may be of shallower depth and the bridging sheets may be smooth, if desired. The partition walls are erected in channels secured to the floor, similar to the channel 6, and are capped by channels similar to the channel 27.

While I have in the above description defined what I believe to be a preferred and practical embodiment of the invention, it will be understood to those skilled in the art that the specific details of construction and arrangement of parts as shown and described are by way of example and not to be construed as limiting the scope of the invention which is defined in the appended claims.

10. What I claim as my invention is:

1. Metallic roof truss construction comprising a joist of corrugated sheet metal having the opposite ends bent up at an acute angle equal to the pitch angle of the roof, and a pair of roof rafters of corrugated sheet metal having their lower ends pocketed within the acute angular portions of said joist and having their upper ends lapped and secured, the corrugations of said joist and rafters extending longitudinally of said members.
15. 2. Metallic roof truss construction comprising a base joist of corrugated sheet metal formed with spaced ridges in the depth direction and lateral flanges, having its opposite end portions upturned at an acute angle equal to the pitch angle of the roof, the ridges in said upturned portions being inverted, and a pair of roof rafters of corrugated sheet metal similarly formed with spaced ridges in a depth direction and lateral flanges, having their lower ends seated in the apices of said acute angles and their lower portions congruently engaging said upturned ends, the upper ends of said rafters being lapped and secured.
20. 3. Metal roof construction comprising a plurality of spaced truss members each comprising a base joist of corrugated sheet metal formed with spaced ridges and lateral flanges, having its opposite end portions upturned at an acute angle to the pitch angle of the roof, with the ridges of said portions inverted, and a pair of roof rafters of corrugated sheet metal similarly formed with spaced ridges and lateral flanges, having their lower ends seated in the apices of said acute angles and their lower portions congruently engaging said upturned end portions, the upper ends of said rafters being lapped and secured, said ridges and said corrugations extending longitudinally of said members, spaced purlins supported upon said rafter perpendicular thereto, each being of corrugated sheet metal with spaced longitudinal ridges and lateral flanges, and corrugated metal sheets upon said purlins and secured thereto.

JOSEPH M. BRINKER.
